SYSTEM FOR TRANSPORTING MATERIALS

Leo J. Vogel, Mount Lebanon, Pa.

Application May 8, 1939, Serial No. 272,371

8 Claims. (Cl. 214—41)

My invention relates to a new and improved system for transporting materials.

One of the objects of the invention is to provide mechanism whereby a suitable carrier, such as a skip car, can automatically take up a predetermined load at a loading station, in order to transport said load to an unloading station.

Another object of the invention is to provide mechanism which is particularly adapted for use in connection with aerial tramways, although the invention is not restricted thereto.

Another object of the invention is to provide mechanism whereby the carrier automatically causes the operation of feeding mechanism and time-control mechanism, when the carrier is moved to the loading position.

Another object of the invention is to provide improved electrical control means for the aforesaid purposes, it being understood that the invention is not limited to electrical control means.

Another object of the invention is to provide a system having a manual hand control, in case it is desired to increase the load of a skip car or other carrier.

Another object of the invention is to provide an automatic control whereby the loading of the carrier is automatically discontinued after a predetermined period of time.

Other objects of my invention will be set forth in the following description and drawings which illustrate a preferred embodiment thereof, it being understood that the above statement of the objects of my invention is intended generally to explain the same without limiting it in any manner.

Fig. 1 is a side elevation of the improved apparatus, partially in section, showing the lower outlet end of the hopper and also showing the auxiliary mechanism for feeding the material from the hopper into the skip-car.

Fig. 2 is a sectional view, partially in plan, on the line 2—2 of Fig. 2.

Fig. 3 is an end elevation on the line 3—3 of Fig. 1.

Fig. 4 is a sectional view on the line 4—4 of Fig. 2. This shows the positions of the parts of the control mechanism, shortly after the skip-car has been moved to loading position, and prior to the completion of the loading of the skip-car. The positions of the control parts correspond to the positions shown in Fig. 8.

Fig. 5 is a sectional view on the line 5—5 of Fig. 4.

Fig. 6 is a detail view of the control mechanism whereby the feeder motor has its circuit

opened by a time-control mechanism, and the circuit of the hauling motor is closed.

Fig. 7 shows the parts illustrated in Fig. 6, in the normal positions of said parts which correspond to Fig. 10.

Fig. 8 is a diagrammatic view of the control circuits and their connections, corresponding to the positions of the parts illustrated in Fig. 4.

Fig. 9 shows the parts illustrated in Fig. 8, in the positions of said parts corresponding to Fig. 6. This view shows the core-plunger 31 in the lower full-line position of Fig. 6, just before the energized solenoid 32 raises said plunger and the rod 7 and the pawl 28, to the upper broken-line positions of Fig. 6.

Fig. 10 shows the parts of Fig. 8 and Fig. 9, in the relative positions corresponding to Fig. 7.

The apparatus comprises a magazine or hopper 1, which receives the material M to be conveyed. A trough 2 is provided with wheels 3, which can move back and forth upon laterally spaced rails 4. Said rails 4 are mounted upon a suitable frame or platform. A lever 5 is pivotally connected at 6 to said frame.

A rod 7 is pivotally connected at 8 to the lever 5. Said rod 7 actuates the mechanism for operating certain of the control parts of the apparatus. The trough 2 is pivotally connected to the lever 5, so that the trough 2 is reciprocated when the lever 5 is rocked. The lever 5 is pivotally connected by means of a link 9 to a disc 10 which is mounted upon the shaft 11.

The shaft 11 is provided with a gear 12, which meshes with the driving gear 14 of an electric motor 15. The operation of the electric motor 15 therefore causes the trough 2 to be reciprocated. The bottom outlet end of the hopper 1 is always open so that material is discharged continuously upon the trough 2. However, the trough 2 is of sufficient depth so as to stop the flow of material out of the hopper 1, when said trough is held stationary under the hopper 1, and the material has been accumulated in said trough up to a predetermined height. The trough 2 has two side walls and a rear wall, and it is open at its front end 2a.

The material M may be pebbles or the like, which are waste material resulting from the treatment of coal in mines and the like. Hence, even though the front end of the trough is open, material can be loaded into said trough, up to a predetermined height.

The skip-car 17 is of usual construction and it is provided with wheels 18, which ride upon suitable rails 19 of the loading platform. The skip-

car is conveyed from the loading station shown in Fig. 1 to any suitable unloading station or stations, by any suitable means. Such means may be an endless cable 21, which is connected to frame 20 of skip-car 17. This cable 21 is driven by hauling motor 22, by connecting means which are not shown, as they are conventional. It is conventional to provide the motor 22 with a control switch which is located at the unloading station (not shown) so that the circuit of motor 22 is opened automatically by the skip-car at the unloading station.

In the particular embodiment shown, the skip-car moves on the track cables of an aerial tramway, when it moves off rails 18.

A casing 23 is located at any suitable place, as for example underneath the feed motor 15. This casing has a shaft 24 provided with a sprocket 25. A chain 26 is connected to said sprocket 25, and a weight 27 is connected to the end of the chain 26.

Referring to Fig. 4, the weight 27 urges the shaft 24 to turn in a clockwise direction.

As shown in Fig. 4, an actuating-pawl 28 is pivotally connected to a collar which is mounted upon the rod 7. When the trough 2 is reciprocated, the rod 7 operates to turn the shaft 24 intermittently in the counter-clockwise direction, so as to raise the weight 27.

The pawl 28 cooperates with a ratchet-disc 29, which is connected to the shaft 24. A stop-pawl 30 is pivotally connected to the head of the core-plunger 31 of a solenoid 32. The pawls 28 and 30 are provided with the usual springs (not shown) for biasing them so that they engage with the teeth of the ratchet-disc 29, when the parts are in the position shown in Fig. 4.

The rod 7 passes slidably through a suitable opening in the head 33 of the core-plunger 31. The ratchet disc 29 is provided with a projecting lug 34. When the ratchet-disc 29 has been turned counterclockwise from the position shown in Fig. 7 to the position shown in Fig. 6, said lug 34 operates the switch arm 35 to the position shown in Fig. 6. In said position the circuit of the motor 15 is opened, and the circuit of the hauling motor 22 is subsequently closed, within a predetermined period of time after the circuit of the motor 15 has been opened. These operations will be later more specifically described.

When the solenoid 32 is energized so as to raise the head 33 to the full-line position shown in Fig. 7, the ratchet disc 29 is free to turn in the clockwise direction until the weight 27 opens the switch 36. This breaks the circuit of the solenoid 32 as will be later more fully described, so that the core plunger 31 then drops back to the position shown in Fig. 4.

When the weight 27 is in the position shown in Fig. 7, the lug 34 contacts with a stop 37, which is adjustable within casing 23, so that said stop can be located at any desired point within said casing. The means for connecting stop 37 adjustably to casing 23 are not shown in the drawings, as said means are conventional. The counterweight 27 can also be adjusted by conventional means, adjusting the length of chain 26, or by adjusting the position of the counterweight 27 on chain 26, so that the weight 27 opens the switch 36 when lug 34 abuts the adjustable stop 37. Hence, the position of the adjustable stop 37 determines the angle through which the ratchet disc 29 is turned counterclockwise, first to close the switch 36 and then to open switch 35.

It will be noted that when the core plunger

31 is raised, the rod 7 is turned upwardly so that the pawls 28 and 30 are released from the teeth of the ratchet disc 29.

Referring to Fig. 8, when the skip-car 17 is moved to the loading position illustrated in Fig. 1, said skip-car moves a switch rod 38 to the left of the position illustrated in Fig. 10. The switch rod 38 is located in a casing 39. A spring 40 normally maintains the switch rod 38 in the position illustrated in Fig. 10.

Fig. 8 shows the switch rod 38 after it has been pushed inwardly from the normal position illustrated in Fig. 10, and when the skip-car 17 is in its loading position.

15 Direct current is supplied to the apparatus from the power mains 41 and 42. Of course alternating current could be used by installing a rectifier. Likewise there are certain types of solenoids of electro-magnets which are energized by alternating current in order to exert a magnetic pull in a fixed direction, and such types of electro-magnets or relays can be used if alternating current is supplied through the mains 41 and 42.

As shown in Fig. 10, the rod 38 has a collar 25 or blade 43, which is normally spaced from the terminals 44. Said rod 38 has a second collar or blade 45 which normally connects the terminals 46.

A third collar or blade 47 is normally spaced from the terminals 48. A fourth collar or blade 49 is normally in contact with the terminals 50. Hence, in the normal position of the switch rod 38 which is shown in Fig. 10, the circuit of the feed motor 15 is open.

30 In the normal position of switch plunger 36a of switch 36, the circuit of the solenoid 32 is also open, as shown in Fig. 10.

As shown in Fig. 10, the upper terminal of the solenoid 32 is connected by the member 45 across the terminals 46 to the power main 42.

40 The lower terminal of the solenoid 32 is connected to one of the terminals 33c of the switch 36. In the normal position shown in Fig. 10, the weight 27 is in its bottom position (this being the position shown in Fig. 7 and also shown in broken lines in Fig. 6), so that the plunger 36a of the switch 36 has been moved against the force of spring 36b so as to break the electrical connection between the terminals 33c. Hence, the lower end of the solenoid 32 is not connected to the main 41, and the circuit of solenoid 32 is open.

45 As the skip-car is moved to the loading position, the rod 38 is moved until it is in the position shown in Fig. 8, so that the circuit of the feed motor 15 is closed through the member 43 and the terminals 44. The loading of the skip-car is thus started. The rod 7 is therefore reciprocated to turn the ratchet wheel 29 counterclockwise, so as to raise the weight 27.

50 In Fig. 8 the weight 27 is shown in the position to which it has been raised after several intermittent movements of the ratchet wheel 29 and prior to the completion of the loading of the car. The compression spring 36b closes the switch 36 as soon as the weight 27 has been raised sufficiently. However, the circuit of the solenoid 32 remains open as long as the member 45 is in the position shown in Fig. 8, namely, during the entire period of the loading of the skip-car. The ratchet-wheel 29 is intermittently actuated until the lug 34 turns the switch-arm 35 against the force of the tension spring 35a which normally holds the switch-arm 35 in the position shown in Fig. 8, against a suitable stop (not shown).

The switch-arm 35 is thus moved to contact with the terminal 35b. The hand-switch H is normally maintained in the position shown in Fig. 8, by means of a suitable compression spring.

Therefore when the switch-arm 35 has been moved to contact with the terminal 35b, a circuit is closed from the main 42, through the terminal 35b, the switch-arm 35, the terminals 60 of the hand-switch H, through the terminals 48 and the member 47, to the right-hand end of the relay R, through relay R to main 41.

The energized relay R moves switch armature 51 from the normal position shown in Fig. 10 to the position shown in Fig. 9, thus breaking the circuit of motor 15, since this circuit includes the switch-armature 51 and the terminals 52. Likewise, when the terminals 53 are connected through the switch-armature 51, this closes the circuit of the hauling motor 22, as illustrated in Fig. 9. This causes the loaded skip-car to be moved away from the platform, thus permitting the member 38 to move outwardly to the normal position illustrated in Fig. 10.

In Fig. 8 the member 38 is shown in its innermost position, corresponding to loading position.

The switch-armature 51 and its terminals 52 thus act as a limit switch or limit-device, to limit the loading of the conveyor. By adjusting the stop 34 on the ratchet-wheel 29, and by adjusting the stop 37, the loading-period can be ended after any desired number of full-feeding strokes, plus any desired fraction of a feeding stroke. The adjustable connection between stops 34 and 37 and their respective supports is conventional and not shown.

In Fig. 9, the member 38 is shown as having moved outwardly to its outermost position, the skip-car now being out of contact with the head of said member 38. Fig. 9 shows the circuit of the hauling motor 22 closed through the member 49 and the terminals 50, so that when the switch-armature 51 is moved to the position shown in Fig. 10, the circuit of the hauling motor 22 remains closed through the terminals 50. Fig. 9 shows the member 31 in its lower position.

The reverse or outer movement of the member 38 connects the terminals 46 through the member 45 so as to energize the solenoid 32, thus upwardly moving the core-plunger 31, and releasing the ratchet disc 29, as shown in Fig. 10, so that the weight 27 is freed to move downwardly.

When the weight 27 descends sufficiently, it opens the switch 36 so as to break the circuit of the solenoid 32. The core plunger 31 then drops under the action of gravity back to the position illustrated in Fig. 4 and also in Fig. 9, so that the apparatus is ready to load another skip-car when said skip-car arrives at the loading platform to push the member 38 inwardly.

The period during which the skip-car is loaded is controlled by the time which is required to turn the shaft 24, so as to move the switch arm 35 from the position shown either in Fig. 8 or in Fig. 10 to the position shown in Fig. 9.

The switch H permits the operator manually to control the loading of the skip-car if the skip-car is oversized or if the material is too fine.

By pressing the switch H downwardly, the connection between the terminals 60 is broken, and the terminals 61 are connected by said hand-switch.

If the connection between the terminals 60 is broken, the relay R cannot be energized so that the circuit of the hauling motor 22 remains open.

Likewise, if the hand-switch is operated, this maintains the circuit of the feeding motor 15 closed so as to feed more material into the skip-car. This additional actuation of the motor 15 would tend to continue the counterclockwise turning of the ratchet wheel 29 beyond the desired angle.

Therefore the ratchet wheel 29 has a portion 65 of its periphery where one or more of the ratchet teeth are omitted.

When the lug 34 has moved the arm 35 to the position shown in Fig. 6 and also in Fig. 9, this portion 65 is directly adjacent the pawl 30 so that the disc 29 and its shaft 24 can oscillate, being turned clockwise by the weight 27 whenever the pawl 28 is moved rearwardly. This prevents overfeeding of the disc 29, if the hand switch is utilized for the aforesaid purpose. Likewise, when the circuit of motor 15 is opened, said motor and the rod 7 continue to operate under their momentum. However, when the circuit of motor 15 is opened, the stop-pawl 30 contacts with the long or idler tooth 65 of the ratchet-disc 29. The ratchet-disc 29 then oscillates idly so that it is not overdriven.

The time-control mechanism therefore includes a movable member 29 which is moved in a predetermined direction, only through a predetermined distance, during each loading period. The time-control mechanism has its own driving means, to wit, the weight 27, for moving said movable member 29 in a reverse direction after a loading period has been completed and before the beginning of the next loading period, to a predetermined initial position.

At the end of a predetermined loading period, the motor-driven load-controlling means can therefore operate under their own momentum, without moving said movable member 29 beyond its predetermined position at the end of a loading period. The drive between motor 15 and member 29 can therefore be designated as a drive which is a lost-motion drive when member 29 has been actuated through said predetermined distance.

The operation of the device is as follows: Before the skip-car arrives at the loading station which is illustrated in Fig. 1, the normal positions of the parts are shown in Fig. 7 and also in Fig. 10. When the skip-car arrives at the loading station, it pushes the switch-rod 38 inwardly against the force of spring 40. This inner position of the switch-rod 38 is shown in Fig. 8.

While the parts are in the normal position illustrated in Fig. 7 and in Fig. 10, the circuit of the feed motor 15 is open because the switch-arm 43 is spaced from the contacts 44. While the parts are in said normal position, the circuit of the hauling motor 22 is closed by member 49 across terminals 50. Lug 34 then abuts the stop 37, which has been adjusted to the desired position and the counterweight 27 holds switch 36 open.

When the switch-rod 38 is pushed into the inner position shown in Fig. 8, the switch-member 43 contacts with the terminals 44, thus closing the circuit of the feed motor 15. The switch-member 49 is now spaced from the contact terminals 50, thus opening the circuit of the hauling motor 22. The feed motor 15 now reciprocates the trough 2 so as to load the skip-car 17. As soon as the motor 15 begins to operate, it reciprocates the rod 7, so as to turn the ratchet disc 29 intermittently by means of the spring-biased pawl 28, thus raising the weight 27 from

the position shown in Fig. 7. When the weight 27 is raised, the plunger 36a of the switch 36 is raised by the spring 36b, until said plunger touches the terminal contacts 36c, thus closing one of the open parts of the circuit of the solenoid 32. The switch 36 is preferably closed, immediately after the feeder begins to operate.

After the feeding motor has operated for a predetermined period, the lug 34 turns the switch-arm 35 against the force of the biasing spring 35a until the switch-arm 35 touches the terminal contact 35b. This energizes the relay R so that the switch-armature 51 is moved from the normal position which is indicated in Fig. 10, to the position which is indicated in Fig. 9. This breaks the circuit of the feeding motor 15 and closes the circuit of the hauling motor 22 so that the hauling motor 22 operates to move the skip-car 17 away from the loading station.

As the car moves away from the loading station, the switch-rod 38 is moved by the spring 40 back to its outer position, which is also illustrated in Fig. 9. This opens the circuit of the feed motor 15 at the contact terminals 44, and closes the circuit of the hauling motor 22 at the contact terminals 50.

When the switch-rod 38 is moved back to its outer position, the circuit of the relay R is broken at the contact terminals 43 so that the member 51 is moved by the spring 51a back to the position which is illustrated in Fig. 10. The skip-car 17 is thereupon moved by the endless cable 21 to the unloading station, at which point the skip-car operates the usual switch for opening the circuit of the hauling motor 22. When the switch 38 has moved back to the position shown in Fig. 8, the circuit of solenoid 38 is closed by member 45, so that core-plunger 31 is raised, thus disengaging the pawls 28 and 30 from the ratchet-wheel 29. The weight 27 thus reversely turns ratchet-wheel 29 to its predetermined initial position, thus opening switch 36 and the respective part of the circuit of the solenoid, and permitting the plunger 31 to descend to its lower position in which the pawls 28 and 30 can engage the ratchet teeth of member 29, only after said member 29 has reached said predetermined initial position. The hauling motor 22 can be manually controlled, if desired, at any suitable station. It has the usual reversing switch (not shown) which is operated automatically by the skip-car so that the motor moves the skip-car back and forth between the loading station and the unloading station, in the well-known manner. This detail is not illustrated, as it is well-known practice.

If it is desired to increase the length of the loading period of the skip-car 17, the hand-switch H is depressed until it closes the circuit across the contact terminals 61. This closes the circuit for the feed motor 15 and it breaks the circuit of the relay R at the contact terminals 60.

While I have shown electrical control means, it would not be departing from the invention to utilize mechanical or hydraulic or pneumatic control means. Likewise the time-control mechanism which is exemplified may be replaced by other time-control means which need not necessarily be operated in unison with the feed motor 15. Switches which are moved manually or automatically to close a circuit and which subsequently open the circuit after a predetermined period of time are well-known on the market as standard articles of commerce, and I can use the same.

While I have shown the use of a single skip car which is moved back and forth between a loading-station and an unloading station, the invention is not limited to such a system, and it includes every type of loading and conveyor system. Whenever I refer in the claims to a single car or conveyor, said claims include a system which utilizes a plurality of cars or conveyors.

10 Various loading systems are well-known which utilize a loading bin having an outlet which is controlled by a gate.

For convenience I have designated certain of the parts by reference letters or characters in certain of the claims. This is not to be understood as limiting the invention.

Another important feature is that the equipment is self-protecting against any undesired condition which might cause it to operate continuously. Since the ratchet teeth are cut away at the zone 65, the mechanism cannot operate when the pawl 38 is at said zone 65. The stop 37 which is shown in Fig. 4 can be adjusted at any part of the circular zone in which the ratchet wheel is located. The switch 35 which is shown in Figs. 8-10 is the equivalent of a fine or micrometer adjustment which will cause the limit switch to trip at any point between full strokes. For example if it is desired to stop the operation of the device after the feeding mechanism has operated for 5½ strokes or 5¼ strokes, the stop 37 can be adjusted so as to give 5 strokes and the change in position with the limiting switch will take care of the fractional part of the stroke.

35 It is well known in loading systems to discharge a predetermined quantity of the material into the loading bin or hopper and to discharge the material from this loading bin or hopper to the skip car or other conveyor, by causing the skip car or other conveyor to trip the loading bin or to open a gate of the loading bin, when the skip car or other conveyor comes to the loading position relative to said loading bin. The invention is therefore not limited to the idea of discharging the material directly into the skip car.

40 In the embodiment disclosed herein the conveyor moves back-and-forth between the loading station and the unloading station. However there are well-known systems in which the conveyors move continuously in a predetermined path, the loading station being located at one part of said path, and the unloading station being located at another part of said path. The invention is therefore not limited to a system in which the conveyor or conveyors move back-and-forth between the loading station and the unloading station.

45 I claim:

1. A system for transporting material, comprising a loading station, feeding means located at said station and adapted to feed said material, an electric feeding motor adapted to actuate said feeding means, a conveyor movable to said station and away therefrom, a second electric motor adapted to actuate said conveyor, first switch means located at said loading station and having a normal position, said first switch means controlling the circuits of said motors and opening the circuit of the feeding motor and closing the circuit of the second motor when the switch means are in said normal position, the circuit of said feeding motor having second switch means which include first spaced terminals, a movable arm associated with said terminals and biased normally to contact with said terminals, a relay

adapted to operate said movable arm, the second motor having second spaced terminals which close the circuit of the second motor when said second spaced terminals are connected by said arm, said arm being mounted to move away from the first terminals and to contact with the second terminals when the relay is energized, time-control mechanism adapted to energize said relay after a predetermined period of time.

2. A system according to claim 1 in which said time-control mechanism is operated in unison with the operation of said feeding motor.

3. A system for transporting material, comprising a loading station, a conveyor movable towards said loading station and away therefrom, feeding means adapted to feed material to the conveyor at the loading station, an electric feeding motor 15 connected to said feeding means, an electric hauling motor 22 adapted to actuate the conveyor towards said station and away therefrom, the circuit of the feeding motor comprising a first pair of separated terminals 44 and a second pair of separated terminals 52, the circuit of the hauling motor comprising a third pair of separated terminals 53 and a fourth pair of separated terminals 50, a solenoid 32 whose circuit comprises a fifth pair of separated terminals 36c and also a sixth pair of separated terminals 46, a relay R whose circuit comprises a seventh pair of separated terminals 48 and an eighth pair of separated terminals 35b, switch means 38 having a normal position, said switch means 38 having a first switch member 43 adjacent and spaced from the first terminals 44 when said switch means 38 are in normal position, said switch means having a second switch member 47 which is adjacent and spaced from the seventh switch terminals 48 when the switch means 38 are in normal position, said switch means 38 having a third switch member 49 which contacts with the fourth terminals 50 when the switch means 38 are in normal position, a switch armature 51 adapted to be operated by the relay R, said switch-armature 51 being biased to normal position in which it contacts with the second terminals 52 and in which it is spaced from the third terminals 53, said switch-armature 51 being operated by said relay R when it is energized to move away from the second terminals 52 and to contact with the third terminals 53 so as to close the circuit of the second electric hauling motor 22, a fourth switch member 36a biased to contact with the fifth terminals 36c, a weight 27 adapted to rest upon the fourth switch member 36a and to hold it out of contact with the fifth terminals 36c, pawl-and-ratchet means operated by the feeding motor 15 and adapted to raise the weight 27 so as to permit the fourth switch member 36a to move to contact with the fifth terminals 36c, means operated by the energizing of the solenoid 32 to move said pawl-and-ratchet means to an inoperative position, a fifth switch member 35 movable to a position in which it contacts with both of the eighth terminals 35b, said fifth switch member 35 being biased to a normal position in which it leaves the circuit between the eighth terminals 35b open, said switch means 38 being located in the path of movement of the skip car so that the skip car is adapted to actuate said switch means 38 until the first switch member 43 contacts with the first terminals 44 and the second switch member 47 contacts with the seventh terminals 48 and the third switch member 49 is spaced from the fourth terminals 50, the ratchet 29 of said pawl-and-ratchet means having a lug 34 adapted to

contact with the fifth switch member 35 and to move said fifth switch member 35 until it contacts with both of the eighth terminals 35b after said ratchet 29 has been turned through a predetermined arc.

4. A device according to claim 3 in which the circuit of the feeding motor includes a ninth pair of terminals 61 and the circuit of the relay includes a tenth pair of spaced terminals 60, a manually operable switch member H biased normally to contact with the tenth terminals 60, said switch member H being movable away from the tenth terminal 60 to contact with the ninth terminal 61.

5. A device according to claim 3 having manually operable switch means adapted to control the circuit of the relay R and of the feeding motor 15, the ratchet of said pawl-and-ratchet means having a smooth portion which permits said ratchet to rock when said smooth portion is adjacent the pawl means of said pawl-and-ratchet means.

6. A system for transporting material, comprising a loading-station, a conveyor movable towards said loading station and away therefrom, power-driven conveyor-actuating mechanism adapted to move the conveyor towards said loading-station into loading position and away from said loading-station, movable load-controlling means located at said loading-station and adapted to control the load which is delivered to said conveyor while the conveyor is located during a loading-period in said loading-position, movable time-control mechanism adapted to control said load-controlling means so as to discontinue the supply of material to the conveyor at the end of a predetermined loading-period, said time-control mechanism including a movable member which is moved in a predetermined direction and only through a predetermined distance during the respective predetermined loading-period, and additional manually controlled means adapted to increase said loading period while said movable member is moved only through said predetermined distance and in said predetermined direction.

7. A system for transporting material, comprising a loading-station, a conveyor movable towards said loading station and away therefrom, power-driven conveyor-actuating mechanism adapted to move the conveyor towards said loading-station into loading position and away from said loading-station, movable load-controlling means located at said loading-station and adapted to control the load which is delivered to said conveyor while the conveyor is located during a loading-period in said loading-position, movable time-control mechanism adapted to control said load-controlling means so as to discontinue the supply of material to the conveyor at the end of a predetermined loading-period, said time-control mechanism including a movable member which is moved in a predetermined direction and only through a predetermined distance during the respective predetermined loading-period, a motor adapted to actuate said load-controlling means and connected to said movable member by a drive which actuates said movable member in said predetermined direction, said drive being a lost-motion drive after said movable member has been moved through said predetermined distance in said predetermined direction.

8. A system for transporting material, comprising a loading-station, a conveyor movable towards said loading-station into loading-position

and away therefrom, power-driven conveyor actuating mechanism adapted to actuate said conveyor into loading-position and away therefrom, motor-driven feeding means adapted to feed a load of material to said conveyor while it is in loading position, a turnable ratchet-disc having a series of operating ratchet-teeth and an idler ratchet tooth which succeeds said operating ratchet teeth, said idler ratchet tooth being longer than the preceding operating ratchet-tooth, an operating pawl connected to the motor of said feeding means and adapted to be reciprocated by said motor so as to contact with successive operating ratchet teeth and to turn said ratchet-disc intermittently in the same direction, a stop-pawl adapted to engage said oper-

ating ratchet-teeth and to prevent the reverse turning of said ratchet-disc, said ratchet-disc being adapted to oscillate idly when said stop-pawl abuts said idler ratchet-tooth, a control member adapted to be operated by said ratchet-disc to shut off the supply of power to said motor when said stop-pawl contacts with said idler ratchet tooth, said ratchet-disc having means adapted to return the same to predetermined initial position when it is released from said pawls, automatic means operated by the movement of the conveyor away from loading position and adapted temporarily to release said ratchet-disc from said pawls so that said ratchet-disc is free to return to its predetermined initial position.
